TRAVELING BAG

David E. Workman, Orange, Calif., assignor to Samsonite Corporation, Denver, Colo.

Filed Aug. 12, 1974, Ser. No. 496,532

Term of patent 14 years

Int. Cl. D3—01

U.S. Cl. D87—5 C

FIG. 1.

FIG. 2.

FIG. 3.

FIG. 4.

FIG. 5.

FIG. 6.

FIG. 1 is a side perspective view of a traveling bag showing my new design;

FIG. 2 is an elevational view of the opposite side thereof;

FIG. 3 is an end elevational view;

FIG. 4 is a bottom plan view;

FIG. 5 is an end elevational view of the side opposite that shown in FIG. 3; and

FIG. 6 is a side perspective view of my design in compressed position.

I claim:

An ornamental design for a traveling bag, as shown.
